His Attorney.

UNITED STATES PATENT OFFICE

WILLIAM B. POTTER, OF SCHENECTADY, NEW YORK, ASSIGNOR TO GENERAL ELECTRIC COMPANY, A CORPORATION OF NEW YORK

DEVICE FOR PRODUCING SOUND

Application filed May 25, 1927. Serial No. 194,181.

My invention relates to devices for producing sound, and has for its principal object the provision of an improved conical diaphragm apparatus which responds faithfully to the impulses imparted to it by an electromagnetic drive or the like.

Various types of conical diaphragm apparatus have been provided in the past. As usually constructed, such apparatus comprise a cone supported by a strip of flexible material which has one of its edges cemented to the periphery of the cone and the other of its edges cemented to a ring or clamped between a pair of circular bands. Uniformity of vibration and faithful production of sound are dependent on the stiffness of the cone. When the edge of the cone is attached to a continuous ring, as in previous constructions, difficulty may be encountered due to the fact that different parts of the cone do not have the same stiffness as a result of which the sound may be distorted. In accordance with my invention this difficulty is avoided by the provision of means for independently adjusting the stiffness of different parts of the cone.

My invention will be better understood from the following description when considered in connection with the accompanying drawings, and its scope will be pointed out in the appended claims.

Referring to the drawings, Fig. 1 shows a conical diaphragm apparatus wherein my invention has been embodied; and Fig. 2 shows certain details of the apparatus.

This apparatus comprises a cone 1 made of paper or the like and attached to a frame 2 by means of a flexible strip 3, which is connected between the periphery of the cone and a plurality of segmental members 4 arranged to be clamped to the frame 2 by the clamps 5. Each of the clamps 5 is provided with a screw 6 which may be loosened or tightened to permit adjustment in the radial tension of the cone. With this construction the stiffness of the cone is readily adjusted so as to be substantially uniform at all points and the distortion of the sound is minimized or altogether avoided.

It will be apparent that other suitable

means, such as lacing, thumb screws, or the like, may be utilized to ensure uniformity in the tightness of the cone throughout its entire area.

The embodiment of the invention illustrated and described herein has been selected for the purpose of clearly setting forth the principles involved. It will be apparent, however, that the invention is susceptible of being modified to meet the different conditions encountered in its use, and I, therefore, aim to cover by the appended claims all modifications within the true spirit and scope of my invention.

What I claim as new and desire to secure by Letters Patent of the United States is:

1. A sound producing apparatus comprising a cone, a plurality of segmental members, and a strip of flexible material interposed between and attached to said members and the periphery of said cone.

2. A sound producing apparatus comprising a support, a diaphragm, a plurality of segmental members, a flexible strip interposed between and attached to said diaphragm and said members, and adjustable means attached to said support for fixing said members to said support.

3. A sound producing apparatus comprising a support, a diaphragm, a plurality of segmental members, a flexible strip interposed between and attached to said diaphragm and said members, and a plurality of adjustable clamps arranged to attach said members to said support.

4. A sound producing apparatus including a hollow cone, and means for supporting said cone including a flexible member attached to the outer edge of the cone and a discontinuous clamping ring attached to said flexible member, said clamping ring having a plurality of portions radially movable independently of each other.

In witness whereof, I have hereunto set my hand this 23rd day of May, 1927.

WILLIAM B. POTTER.
